UNITED STATES PATENT OFFICE.

MIROSLAV PILNY, OF ASTORIA, NEW YORK, ASSIGNOR TO METROPOLITAN-COLUMBIA MFG. CO. INC., A CORPORATION OF NEW YORK.

DESIGN FOR AN ARM FOR LIGHTING FIXTURES.

Application filed July 30, 1925. Serial No. 14,279. Term of patent 3½ years.

To all whom it may concern:

Be it known that I, MIROSLAV PILNY, a citizen of the Republic of Czechoslovakia, and a resident of Astoria, county of Queens, and State of New York, have invented a new, original, and ornamental Design for Arm for Lighting Fixtures, of which the following is a specification, reference being

had to the accompanying drawing, forming a part thereof.

The drawing shows a perspective view of the arm for lighting fixtures.

I claim:

The ornamental design for an arm for lighting fixtures, substantially as shown.

MIROSLAV PILNY.
